SWING

Robert A. Gazella, Ionia, Mich.

Application March 4, 1947, Serial No. 732,217

1 Claim. (Cl. 155—63)

1

This invention relates to swings and more particularly to swings having a foot pedal and handle bar by which the rider may propel the swing.

It is an object of this invention to provide an improved swing of the kind to be more particularly described hereinafter having a seat frame for supporting one or two seats and a handle bar and foot pedal lever pivotally mounted on the frame by which the rider or riders may propel the swing by rocking the lever. The seat frame and swing operating lever are suspended by substantially parallel chains or cords from a fixed support so that a force exerted on the lever will be carried into the seat frame.

Another object of this invention is to provide an improved swing of this kind having a seat frame suspended by a pair of longitudinally spaced apart parallel flexible supporting members whereby the position of the seat relative to the ground will remain the same, i. e., parallel, in all positions of the swing throughout the arc of its travel. The seat suspension is substantially a four bar linkage so the seat when initially set parallel to the upper bar of the fixed supporting frame will remain parallel during the arc of the swing.

Still another object of this invention is to provide an improved swing of this kind having a seat frame that is very light and strong providing an efficient swing suitable for the hard use and abuse to which devices of this kind are subjected by children.

A further object of this invention is to provide a handle bar on a device of this kind which is freely rotatable whereby the handle will rotate about its support on the operating lever while being held firmly in the grip of a rider as the position of the rider relative to the flexible supporting members changes in the movement of the swing.

A still further object of this invention is to provide a guard rail about the seat of the swing for holding a small child and preventing him from sliding from the swing inadvertently.

With the above and other objects in view, my invention consists in the arrangement, combination and details of construction disclosed in the drawings and specification, and then more particularly pointed out in the appended claim.

In the drawings:

Figure 1 is a side elevation of an improved swing constructed according to an embodiment of this invention.

Figure 2 is a transverse section taken on the line 2—2 of Figure 1.

2

Figure 3 is a vertical section taken on the line 3—3 of Figure 1.

Figure 4 is a horizontal section taken on the line 4—4 of Figure 1.

Figure 5 is a longitudinal section taken on the line 5—5 of Figure 4.

Figure 6 is a transverse section taken on the line 6—6 of Figure 3.

Referring to the drawings, the numeral 10 designates generally an improved swing having means for actuating the swing by a person riding thereon. The numeral 11 designates generally a fixed frame from which the swing and the operating member depend. The frame 11 is formed of a pair of upright supporting bars 12 at each end and longitudinally extending horizontal supporting members 14 fixed between the upper ends of the upright bars 12 at each side of the frame.

A transverse bar 15 is fixed horizontally between the opposed pairs of upright members 12 at the upper ends thereof at each end of the frame and a central transverse bar 16 is fixed between the horizontal bars 14 midway the length thereof.

The swing 17 is supported by flexible members as chains or cords 18 which are fixed at their upper end to the transverse bars 15 and at their lower end to the swing frame 17. The swing frame 17 is formed of an elongated strip of metal or other suitable material, bent to form a seat frame 19 and having a central longitudinal forwardly extending bar 20 integral therewith.

The front end of the seat frame is formed concave as at 21 on each side of the center line 35 through the seat to provide for the comfortable position of the legs of the rider with the frame bar sides converging and meeting at the center of the front of each seat in tapered formation and the bars 20 contiguous or brought together 40 in contact. The seat 17 may be formed, as shown in Figure 1, with a pair of oppositely disposed seat frames 19 rigidly connected together by the bars 20.

A seat cover as 22 is adapted to be placed above 45 the seat frame 19 to provide a seat thereon. A guard rail 24, which is substantially U-shaped in plan view, is fixed to or formed on each of the seat frames 19 opening forwardly towards the center of the swing. The guard rail 24 is formed

50 of a U-shaped bar 25 fixed above the frame 19 by upright bars or posts 26 at the back and sides of the seat and guard rail, the posts 26 at the sides being bent down from the ends of bar 25. A transverse bar or supporting member 27 is 55 fixed to the lower side of the seat frame 19 near

the rear or outer end thereof and plates 28 are fixed on each end of the bar 27 to which the lower links of the chains 18 are adapted to be engaged or pivotally connected.

An operating lever 30 is pivotally or rockably mounted on the forwardly extending bar 20 on the seat frame 11 spaced from the seats centrally of the length of said connecting bars. The lever 30 is formed of a pair of metal bars 31 spaced apart at their lower end so that the bars 31 are adapted to engage about the connecting bar 20. A pivot pin 32 engages through the arms 31 and through the bar 20.

Transversely extending foot pedals 33 are fixed to the lower end of the arms 31 and extend outwardly therefrom to be engaged by the feet of the rider for rocking the lever 30. Upwardly extending lugs 34 are fixed on the outer end of the foot pedal 33 to prevent the foot of the rider from sliding off of the pedal.

A transverse handle bar 35 is fixed to the upper end of the lever 30, extending outwardly from both sides thereof. A small plate 36 is fixed to the outer ends of the handle bar 35 by a bolt 37 or other suitable attaching means, and a tubular handle grip 38 is loosely mounted on the bar 35. The handle grip 38 is disposed between the arms 31 and the lugs 36 to hold the grip 38 against lateral movement.

The grip 38 may be grasped tightly by the rider and may be rotated to suit the position of the hands relative to the lever 30 and the handle bar 35. A flexible operating member as the chain 39 is fixed between the lugs 36 and the central transverse bar 16. Rocking movement of the lever 30 relative to the frame 11 will effect oscillating or swinging movement of the swing 17 relative to the frame 11.

In the use and operation of this swing, the propulsion of the swing may be effected by the rider or riders by rocking the lever 30 either by way of the foot pedals 33 or by means of the handle bar 35 or both. A swing constructed in this manner may be built very light, and having a minimum number of parts will require practically no attention for maintaining the swing in usable condition.

The flexible supporting members 18, and operating members 39 are substantially parallel as shown in Figure 1, which will provide for the maximum movement to be derived by rocking movement of the lever 30. While the parallel

disposition of these flexible members will provide for the most efficient arrangement, the members may be otherwise disposed so that the operating member 39 will be forward of the supporting member 18.

I do not mean to confine myself to the exact details of construction herein disclosed, but claim all variations falling within the purview of the appended claim.

10 What I claim is:

A swing comprising a seat structure constituted of an elongated bar bent to form spaced horizontal loops forming seat frames facing each other, said bar being brought together centrally at the inner sides of the seat frames to form a rigid horizontal connection between the seat frames, seat covers on said seat frames, a vertical operating lever pivotally connected to the connections between the seat frames and comprising a pair of bars straddling the connection and brought together at their upper end portions, a foot bar secured to the lower end of the lever and extending from opposite sides thereof, a handle bar mounted through the upper end 15 of the lever and projecting from opposite sides thereof, tubular handles on the bar at opposite sides of the lever, retaining means for said handles at the ends of the handle bar, a transverse bar secured to the lower side of each seat frame 20 comprising a pair of bars straddling the connection and brought together at their upper end portions, a foot bar secured to the lower end of the lever and extending from opposite sides thereof, a handle bar mounted through the upper end 25 of the lever and projecting from opposite sides thereof, tubular handles on the bar at opposite sides of the lever, retaining means for said handles at the ends of the handle bar, a transverse bar secured to the lower side of each seat frame 30 comprising a pair of bars straddling the connection and brought together at their upper end portions, a foot bar secured to the lower end of the lever and extending from opposite sides thereof, a handle bar mounted through the upper end 35 of the lever and projecting from opposite sides thereof, tubular handles on the bar at opposite sides of the lever, retaining means for said handles at the ends of the handle bar, a transverse bar secured to the lower side of each seat frame

near the outer ends thereof and projecting from opposite sides of the seat frames, pairs of spaced flexible members suspended from above and connected at their lower ends to the ends of the transverse bars at opposite sides of the seats, and a pair of flexible operating members suspended from above and connected at their lower ends to the handle bar at spaced points on opposite sides of the lever.
